UNITED STATES PATENT OFFICE.

CYRUS M. BOSWORTH, OF CLEVELAND, AND ALOYSIUS G. BOESEL, OF CLEVELAND HEIGHTS, OHIO.

ELECTRIC WATER HEATER.

1,415,015.

Specification of Letters Patent. Patented May 9, 1922.

Application filed August 6, 1919. Serial No. 315,586.

To all whom it may concern:

Be it known that we, CYRUS M. BOSWORTH and ALOYSIUS G. BOESEL, citizens of the United States, respectively, and residents of Cleveland and Cleveland Heights, county of Cuyahoga, and State of Ohio, have jointly invented a new and useful Improvement in Electric Water Heaters, of which the following is a specification, the principle of the invention being herein explained and the best mode in which we have contemplated applying that principle, so as to distinguish it from other inventions.

The present invention relates as indicated to water heaters and more particularly to one in which the water is heated by means of an electrically heated element installed in the water circuit between the supply and the storage tank, and also to means for automatically controlling the temperature of the water. The heater is attached to the water tank in a manner similar to the attachment of the usual gas heater. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawings:—

Fig. 1 is an elevation of a storage tank showing my heating device attached thereto. Fig. 2 is an elevation of the heating element showing the casing in section. Fig. 3 is a section at right angles to that of Fig. 2. Fig. 4 is a section on the line 4—4 Fig. 3. Fig. 5 is an elevation of the regulator. Fig. 6 is a section on the line 6—6 Fig. 5. Fig. 7 is a plan view of one of the members of the regulator. Fig. 8 is a section through the switch and Fig. 9 is a modified form of housing for the thermostat.

As is customary in devices of this class, the heater 1 is connected to the storage tank 2 by means of the usual water inlet pipe 3 and outlet pipe 4. The heater proper comprises a casing or housing 5, having screw threaded engagement at its upper end with the outlet pipe 4. Disposed in the upper part of the casing 5 is the heating element or resistor 6 which consists of a channel shaped

member 7 provided with fins or flanges 8 of heat-conducting material. Embedded in the channel-shaped portion 53 of the member 7 is the heating element proper comprising a circuit of resistance wire 54 embedded in a 60 filler of insulating material, such as enamel or the like. A boss or projection 9 integral with the resistor 6 passes through the upper wall 10 of the casing 5 and is threaded at its outer end to engage a packing nut 11. A 65 washer 12 and packing 13 are provided whereby a water-tight joint is formed between the casing 5 and the resistor 6. The boss 9 is provided with a passage way 9', through which wires are passed to the heating element. The passageway 9' is also filled with an insulating material similar to that with which the channel 53 is filled.

Passing through the wall 14 of the casing 5 at a point beneath the resistor 6 and extending into the interior thereof is a shaft 15. A thermostatic coil 16 is spirally coiled about the shaft 15 having its inner end attached thereto. The outer end of the coil 16 is riveted or otherwise connected to a plate 17 bolted to the lower surface 18 of the casing 5. A pin 19 and a washer 20 prevent movement of the coil 16 along the shaft 15. The lowermost portion of the casing 5 is enlarged and has screw threaded engagement 85 with a base piece 21 which is connected to the inlet pipe 3. As will be seen this construction provides an entirely closed-in casing within the water circuit, having both the heating element and the thermostat enclosed 90 therein.

The end 25 of the shaft 15, projecting beyond the wall 14 is provided with an enlarged frusto-conical shaped portion 26 having a plurality of slots 27 milled or otherwise cut in the surface thereof. A dog or operating lever 28, having a complementary recess 29 is adapted to fit the portion 26 of the shaft 15, and is provided with a keyway 30 having a key 29 adapted to engage one 100 of the slots 27 in the portion 26 by means of which any movement of the shaft 15 is imparted to the dog 28. An arm 31 extends from the dog 28 and has a projection 32 extending from the upper end thereof at 105 right angles to the plane of such dog.

Mounted on the shaft 15 is a dial 33 provided with calibrations 34 indicating progressive degrees of temperatures, the calibrations corresponding to the number of 110

slots in the frusto conical shaped portion 26. A pin 35 passes through the dial 33 and engages a hole 36 in the portion 26 on the shaft 15. The outer end 37 of the shaft is 5 threaded and is provided with a wing nut 38 whereby the dial 33 and the dog 28 are held in engagement on the shaft 15. This combination of parts, together with the switch to be described, forms a means of 10 regulating the temperature of the resistor.

Supported on the wall 14 of the casing 5 is a switch 40 provided with contact members 41 and 42 and having movably mounted therein the usual spring controlled circuit breaker 43. Movably mounted upon the center 44 in the switch 40 is an operating arm 45 approximately triangular in shape having two projecting ears or lugs 46 which are adapted to be engaged by the projection 20 32 extending from the upper end of the dog 28.

A housing 50 surrounds the casing 5, and is provided with a door 51, whereby adjustments can be made to the switch or regulator.

25 By means of the combination above described, it is possible to control the temperature of the water between predetermined degrees since any movement of the thermostat coil 16 will rotate the shaft 15, which in turn 30 will move the arm 31 of the dog 28. The projection 32 on the arm 31 contacts with either one of the lugs 46 of the switch operating arm 45 and opens or closes the switch 45, depending on whether the thermostat is 35 expanding or contracting.

The lever arm 31 can be set at any degree of temperature it is desired to heat the water, by removing the dog 28 from the portion 26 and fitting the key 30 into the milled 40 slot 27 corresponding to the temperature desired. By this means, while a certain range of movement is at all times permitted the arm 31 before it contacts with the lugs 46 on the switch operating lever 45, either to 45 close or break the circuit, the temperature at which such closing or breaking occurs may be varied as desired.

As soon as the water has cooled somewhat the thermostat contracts and rocks the arm 50 15 in a reverse direction until the lug 32 on the arm 31 again contacts the switch-operating lever 45 and closes the circuit. By this means an approximately constant temperature is maintained in the storage tank.

55 In Fig. 9, we have shown a modified form of mounting for the thermostat and regulator. The thermostat 60 is coiled about a shaft 61 corresponding to the shaft 15 and has its inner end engaging a slot 62 therein.

60 The outer end of the thermostat coil engages a pin or stud 63 carried by a base piece 64. The base piece 64 has threaded engagement with a housing 65 adapted to enclose the thermostat 60 and close it off from the water 65 passage in the casing 5. The housing 65

may contain simply air, but preferably is partially filled with a fluid 66 which surrounds the thermostat 60. The construction of the regulator is the same as that employed on the previously described form.

As will be seen from the above description and the drawings we have constructed a water heater for storage tanks which is simple in construction and operation, and one in which the temperature is automatically controlled at a predetermined temperature. The device is of few parts and is adapted to be installed in the system without any changes in the piping as used for the ordinary gas heaters in use at the present time. 70 75 80

Other modes of applying the principle of our invention may be employed instead of the one explained, change being made as regards the mechanism herein disclosed, provided the means stated by any of the following claims or the equivalent of such stated means be employed. 85

We therefore particularly point out and distinctly claim as our invention:—

1. In an electrical heating device for water systems of the character described, the combination of a thermostat disposed within said device, and a regulator operatively connected to said thermostat, said regulator comprising a frusto-conical shaped portion, 90 and a switch operating lever adjustably mounted on said frusto-conical shaped portion.

2. In an electrical heating device for water systems of the character described, the combination of a thermostat disposed within said device, and a regulator operatively connected to said thermostat, said regulator comprising a frusto-conical shaped portion, 95 having slots therein, a switch operating lever having a key adapted to engage one of such slots in said frusto-conical shaped portion and a dial attached to said frusto-conical shaped portion. 100 105

3. In an electrical heating device for water systems of the character described, the combination of a thermostat disposed within said device, and a regulator operatively connected to said thermostat, said regulator comprising a frusto-conical shaped portion, 110 having slots therein, a switch operating lever having a key adapted to engage one of such slots in said frusto-conical shaped portion and a dial attached to said frusto-conical shaped portion, the calibrations on said 115 dial corresponding to such slots on said frusto-conical shaped portion.

4. In an electrical heating device for water systems of the character described, the combination of a thermostat disposed within said device, and a regulator operatively connected to said thermostat, said regulator comprising a frusto-conical shaped portion, 120 having slots therein, a switch operating lever having a key adapted to engage one of 125 such slots in said frusto-conical shaped portion and a dial attached to said frusto-conical shaped portion. 130

such slots in said frusto-conical shaped portion, a dial attached to said frusto-conical shaped portion, the calibrations on said dial corresponding to such slots on said frusto-conical shaped portion, and a switch adapted to be opened or closed by such switch operating lever, said switch operating lever being operable by the thermal condition of the fluid in said heating device. 15

5. In a device of the character described, the combination of a casing having a fluid inlet and outlet, a heating element mounted

in said casing, a housing adapted to contain a fluid mounted within said casing, a thermostat disposed within said housing, a regulator mounted on said housing, said regulator being operatively connected to said thermostat, and a switch adapted to be opened and closed by said regulator at a predetermined thermal condition of the fluid 20 in said casing.

Signed by us this 4th day of August, 1919.

CYRUS M. BOSWORTH.

ALOYSIUS G. BOESEL.
